THEODORE H. ICKENROTH, OF LOMITA PARK, CALIFORNIA

OIL BURNER

Application filed January 5, 1929. Serial No. 330,636.

This invention relates to improvements in liquid fuel burners and resides in the provision of a simply constructed, inexpensive and efficient oil burner which is particularly adapted for use in stoves, ranges, and the like and also in furnaces; the construction and arrangement of the burner of this invention providing for thorough vaporization of low grade, as low as 32° gravity, fuel and for proper and effective combustion of the vaporized fuel without the use of forced draft.

One of the purposes of the invention is to provide a burner of the character described which will produce a hot flame for heavy duty as required in hotel and restaurant ranges, furnaces and boilers, with a low fuel consumption and without a forced draft.

A further object is to provide an oil burner of the character described which may be readily and easily taken down and ready access had thereto for cleaning or repair thereof.

The burner of this invention is characterized by a novel form of distributing head in which a thorough and effective vaporization and the proper atomization of the fuel are provided for.

With the above mentioned and other objects in view, the invention consists in the novel construction and combination of parts hereinafter described, illustrated in the accompanying drawings, and set forth in the claims hereto appended, it being understood that various changes in the form, proportion, size and minor details of construction within the scope of the claims may be resorted to without departing from the spirit or sacrificing any of the advantages of the invention.

Referring to the drawings:

Fig. 1 represents a vertical sectional view of a burner constructed in accordance with this invention and appearing as when installed in a stove or furnace.

Fig. 2 represents a horizontal sectional view taken on the plane of line 2—2 of Fig. 1. The preferred embodiment of this invention as illustrated in detail in the accompanying drawings comprises an annular ring or frame member 1 of angular form in cross section and adapted for attaching to the

burner in the fire box of a stove or furnace. An annular plate 2 is removably supported in the open frame 1, there being co-acting lugs 3 and 4 on the ring and plate for this purpose. This plate is provided with an annular trough 5 for oil to be ignited in starting the burner. It is also provided with a central air intake opening 6, through which the oil feed pipe 7 extends upwardly. This air intake opening is screw threaded and receives an externally threaded sleeve 8 having an inwardly extending annular flange 9, the upper side of which is beveled as at 10. The size of the air intake opening is varied by vertical adjustment of this sleeve and flange and the amount of air to the burner may be easily regulated by this arrangement. The upper end of the pipe 7 screws into a nipple 11 which depends from the center of a dome-like vapor generating chamber 12 which latter is thus supported by the feed pipe in upwardly spaced relation to the plate 2.

The chamber 12 is made of two parts, the lower of which is in the form of saucer-like plate 13 with upturned outer edges, which latter abut the lower edges of an approximately semi-spherical upper part 14 of the chamber. Formed centrally of and on the upper side of the part 13 is an upstanding cylindrical enlargement 15, from the upper end of which a projection 16 extends and is socketed in a depending boss 16' on the upper part 14 of the chamber.

Oil from the feed pipe 7 will pass into an upright bore 17 in said member 15 and from thence into the chamber 12 through lateral passages 18 formed in the member 15.

An annular concavo-convex shield 19 is supported on the member 15 with its concave side opposed to the plate-like part 13 of said chamber, and its periphery spaced from the said part 13. Vapors generated in the chamber 12 are caused to pass upward around the outer periphery of said shield in order to be discharged from the chamber through a plurality of vertically disposed outlet passages 20 formed in the member 15. These passages open near the center of the under side of the chamber 12 into the combustion and mixing space provided between

the chamber 12 and the plate 2. An annular baffle plate 21 is mounted on the nipple 11 and extends between the outlet ends of the passage 20 and the air intake opening 6 in the plate 2. This plate causes the air and oil vapors to travel unmixed, a short distance laterally into the combustion space before mixing and by this arrangement, a better atomization of the fuel takes place at and 10 adjacent to the periphery of said baffle plate, which latter rests on lugs 22 carried by the plate 2.

In the operation of the burner of this invention, assuming that it is installed in a 15 stove or furnace or other apparatus, and is arranged as shown in Fig. 1, with the pipe 7 connected with a suitable source of fuel supply, not shown, on turning on the fuel so that it will flow into the chamber 12, a suitable 20 amount of liquid fuel will seep through the joint at the point X and drop into the trough 5. This oil is ignited so that the heat generated will bring about a vaporization of the fuel contained in the chamber 12. The liquid 25 fuel passes from the lateral passages 18 into the saucer-like bottom 13 and gravitates towards the outer perimeter of said bottom. This liquid fuel flowing over the heated part 13 is readily vaporized and the vapors pass 30 upward around the shield 19 and then pass downward through the discharge passages 20 into the space between the bottom of the chamber 12 and the plate 2. The fuel then passes laterally over the top of the baffle plate 35 21 where at the outer periphery of said plate, it encounters currents of atmospheric air and admixture of the air and fuel takes place at this point. The flames are directed outward and upward around the chamber from 40 underneath the same. The atmospheric air passes up through the opening 6 between the sleeve 8, pipe 7 and baffle plate 21. The amount of atmospheric air admitted to support combustion is regulated by adjustment 45 of the sleeve 8. When the sleeve is moved upward, the beveled face 10 of the flange 9 is moved closer to the nipple 11 and plate 21, thereby restricting the air passage and shutting down the air supply. In causing the 50 air and vaporized fuel to be directed outwardly and laterally a short distance before commingling, a better atomization of the vaporized fuel is provided for and a hot and effective flame is produced. The flame, in 55 forming beneath the chamber, then passing upward and around the edge of the same, provides for effective heating of the lower part of the chamber and assures a proper vaporization of the liquid fuel as it flows 60 downward along said part 13 of the vaporizing chamber. The vapor instead of being directed downwardly as is customary in burners of this type, is caused to be passed upwardly around the shield 19 which acts 65 as a baffle, and the complete vaporization

takes place before the fuel can be discharged into the combustion chamber through the passages 20. In this way the fuel is thoroughly vaporized by the time it is discharged and no raw fuel can escape. The shield 19 70 prevents that portion of the part 13 over which the fuel flows during vaporization, from becoming overheated. The heat from the upper portion 14 of the chamber 12 would 75 overheat the plate or part 13 and cause a carbon encrustation to form in the chamber if it were not for the presence of the shield 19 and in this way said shield serves 80 a two-fold purpose inasmuch as it also causes an upward passage of vapor over it before discharge of vapor from the chamber. After initial use of the burner, the oil will seep through the joint of the parts 13 and 14 comprising said chamber 12, and drop into the trough 5 so that there will be ready at all 85 times for ignition, a suitable quantity of fuel to heat the vaporizing chamber at the starting of the burner operation. If desired, a pilot burner indicated by the numeral 23, may be employed, said burner being 90 connected with a suitable source of gas or other fuel, not shown.

The burner of this invention operates without causing objectionable carbon formations or deposits. Another advantage of this invention is the provision for a quick and easy repairing or cleaning of the burner. It is only necessary to disconnect the pipe 7 from its line of supply of fuel, not shown, then turn the pipe 7 so as to disengage the co-acting lugs 3 and 4 to provide for removal of the burner. After this adjustment of the burner it may be readily lowered through the ring or frame 1 and then removed from the firebox. 105

The baffle plate 21 prevents condensation of fuel vapors at a point immediately over the air intake opening 6 and thereby prevents dropping of oil down through said opening. This plate also prevents combustion from taking place immediately at the outlet ends of the passages 20 and by this arrangement, the combustion does not take place until the vapors and air have passed laterally away from said passages 20 a short distance. The combustion becomes greater towards the outer edge of the chamber 12 and is complete at points over the annular air space 24 defined between the plate 2 and frame 1. The sleeve 8 is adjusted to regulate the amount of air passing through the intake opening 6, in consideration of the draft force in the stove or furnace in which the burner is installed. This adjustment is such as to permit just sufficient air to cause a gradually increasing combustion towards the outer edge of the chamber 12 rather than a full, sudden combustion. By this arrangement proper and effective combustion is provided for without appreciable noise. The passages 20 115 120 125 130

are in the form of arcuate slots to provide for a better and more even distribution of the fuel resulting in a better and more even flame.

5 I claim:

1. A liquid fuel burner comprising an open frame; a plate mounted in said frame, being imperforate except for a central or intake opening; a fuel feed pipe extending upwardly through said opening; a closed atomizing chamber mounted on and supported by said pipe above and in spaced relation to the plate, said chamber having passages in the walls thereof communicating the pipe with the interior thereof and being provided with outlet openings to discharge vaporized fuel into the space between the chamber and plate; a baffle member in the chamber above the fuel intake opening around and over which baffle member the vaporized fuel must pass through the discharge opening; a baffle plate between the air intake opening and discharge opening causing a lateral movement of air and vaporized fuel before commingling of said air and vaporized fuel; and means removably supporting said plate on said frame, releasing said plate on predetermined movement of the latter, said plate and chamber being lowerable through the frame.
2. A liquid fuel burner comprising a closed vaporizing chamber having a fuel intake opening on its lower side and provided with a vapor discharge opening, the entrance of which is disposed above the plane of the discharge end of the fuel intake opening within said chamber, and the outlet of which vapor discharge opening is disposed adjacent to the central portion of the under side of the chamber; a baffle plate mounted above the bottom of the chamber interiorly thereof, with its outer periphery disposed close to but spaced upwardly from the bottom of the chamber adjacent the outer wall of the latter, over the top of which baffle plate, fuel vapor passes into said discharge opening, a base spaced from the bottom of chamber having an air intake opening opposite said vapor discharge opening; and a second baffle plate disposed between the vapor discharge and the said air intake openings to cause lateral movement of the air and of the vaporized fuel before commingling of said air and vaporized fuel.
3. A liquid fuel burner comprising a closed vaporizing chamber, a central enlargement interiorly thereof, projecting upwardly from the bottom of the chamber, said enlargement having a fuel intake passage extending first upwardly, then laterally therein, and being also provided with fuel discharge openings extending vertically therethrough, with their intake ends disposed above the plane of the discharge ends of the intake passage, and the discharge ends of said openings located close to the center of the lower side of the chamber;

and an annular plate of substantially concavo-convex form supported by said enlargement in upwardly spaced relation to the bottom of the chamber and with its outer periphery spaced from the adjacent walls of the chamber to provide an annular passage for vapor, upwardly through which passage the vapor will rise towards said discharge openings.

4. A liquid fuel burner comprising an open frame; a plate mounted on the frame, being imperforate except for an air intake opening thereon; a fuel feed pipe extending upwardly through said opening; a closed atomizing chamber mounted on the pipe above and in spaced relation to the plate, a baffle member in the chamber disposed between the bottom and the top of the chamber and being spaced from the circumferential wall of the chamber, said chamber having passages in the central walls thereof to connect said feed pipe with the interior of the chamber below the baffle plate, and being provided with vapor outlet openings connecting the interior of the chamber above the baffle plate with the space between the chamber and the plate, said vapor outlet passages discharging the vapor at a point substantially opposite the said air intake opening; and a baffle plate between the air intake opening and the discharge of the outlet passages causing lateral movement of air and vaporized fuel before commingling of said air and vaporized fuel.

5. A liquid fuel burner comprising an open frame; a plate mounted on the frame, being imperforate except for an air intake opening thereon; a fuel feed pipe extending upwardly through said opening; a closed atomizing chamber mounted on the pipe above and in spaced relation to the plate, a baffle member in the chamber disposed between the bottom and the top of the chamber and being spaced from the circumferential wall of the chamber, said chamber having passages in the central walls thereof to connect said feed pipe with the interior of the chamber below the baffle plate, and being provided with vapor outlet openings connecting the interior of the chamber above the baffle plate with the space between the chamber and the plate, said vapor outlet passages discharging the vapor at a point substantially opposite the said air intake opening; a baffle plate between the air intake opening and the discharge of the outlet passages causing lateral movement of air and vaporized fuel before commingling of said air and vaporized fuel; and means for varying the size of the said air intake opening.
